UNITED STATES PATENT OFFICE.

CLINTON H. LEGGETT, OF NEW YORK, N. Y.

ADVERTISING OR AMUSEMENT DEVICE.

1,346,219.

Specification of Letters Patent. Patented July 13, 1920.

Application filed August 4, 1919. Serial No. 315,069.

To all whom it may concern:

Be it known that I, CLINTON H. LEGGETT, a citizen of the United States of America, residing in the borough of Manhattan, city, 5 county, and State of New York, have invented certain new and useful Improvements in Advertising or Amusement Devices, of which the following is a specification.

10 The present invention provides a device, preferably motor actuated, adapted to put various objects in motion such as figures, or toys, etc., for the purpose of attracting the attention of persons. The device is primarily intended to be placed in show windows to attract the attention of passersby. The actuating device is one which is capable of having the animated objects substituted, so that different figures or objects may be 15 put in motion.

20 The invention further provides a construction or arrangement whereby the various parts may perform their movements without producing objectionable noises.

25 The invention further provides novel movable figures or devices.

Other features of the invention will be hereafter referred to.

30 Embodiments of the invention are illustrated in the accompanying drawing, where-
in—

35 Figure 1, is a vertical sectional view of a device embodying the invention, the figures on the platform being containers of the articles to be advertised, together with a movable sign device.

Fig. 2 is an underside view of the parts shown in Fig. 1.

40 Figs. 3 and 4 are respectively a top plan and a vertical sectional view of a holder for removable signs or the like.

45 Figs. 5 and 6 are respectively a view of animated figures in the form of a pugilist and a cockroach.

Fig. 7 shows an article to be advertised, in the form of a pair of containers or cartons.

50 Referring to said drawings, number 1 designates a vibratory frame of any suitable construction, preferably motor actuated, and having an up and down movement imparted thereto, by means of a motor, 3, belts and pulleys, 4—5—6—7—8, a crank 9, a link, 10 and a bracket or part 12 on the frame 1.

55 The vibratory frame 1, and actuating parts, are preferably housed within a cabinet or

casing, 15, having a top which conveniently forms a platform for the animated or movable figures.

The vibratory frame is conveniently provided with one or more socket pieces, 19—19, which conveniently extend through openings, 20, in the platform 17.

23—24—25—26—27—28 indicate articles adapted to be put in motion by the vibratory frame 1. The articles designated by the numerals 23, 25, 26 are represented as containers or cartons for the materials or things to be advertised. 24 designates a sign holder or carrier. The figure designated by the numeral 27 represents a man, and the figure designated by the numeral 28, represents an insect, that shown being a cockroach.

75 The various figures or parts 23 to 28 inclusive are provided with rods, 30, which are conveniently arranged to set within or telescope with the socket pieces, 19, upon the vibratory frame 1. Preferably the ends of the rods 30 do not bear on or come in contact 80 with the bottoms of the socket pieces. The rods or figures bear upon the socket pieces 19, through the intermediary of stops 32, these stops being preferably provided with central orifices, 33, through which the stem 85 30 passes, the stem acting as a guide for the stops. Between the stops 32, and the shoulder, 35, on the rod 30, Fig. 1, or between said stops and the under side 36, Figs. 4 and 5, of the figure there is arranged a resilient 90 part preferably in the form of a coiled spring, 38. As the frame 1 vibrates up and down, figures 23 to 28 inclusive will be correspondingly moved. The stops 32 are cushioned, thereby diminishing the noise 95 when the stroke or blow of the socket pieces makes contact with the stops.

100 The rods 30 are also preferably loose or rotatable in the socket pieces 19, whereby the articles may turn, and means are preferably provided for imparting a turning or rotary movement to said articles 23 to 28 inclusive, as they are moved or vibrated up and down. Means for rotating the articles are preferably a spring 40, attached to the 105 figure for example, as indicated in 41. The spring is preferably in the form of a coiled spring, and this coiled spring is preferably looped as shown in Figs. 1, 4 and 7.

110 As shown in Figs. 5, 6, the coiled spring may be attached to a dependent part of the figure, as for example to leg 42. Where

the spring is attached to a leg, one joint as for example the knee joint 43, may be pivoted. The joint at the thigh as indicated at 44, is, however, preferably rigid or stiff. 5 The figure may be provided with another leg or legs, and this other leg or legs, may be hinged or pivoted at the knee and thigh as indicated in 48, and 49, Figs. 5 and 6.

As shown more particularly in Figs. 1, 10 3 and 4 one figure, indicated by the numeral 24, may be a sign holder or carrier. This sign holder or carrier preferably comprises a head piece or the like, 50. This preferably has a plurality of signs, 52. The 15 cards or signs 52 are preferably removably connected to the head piece and to this end the head piece 50 is conveniently provided with means for removably holding the cards, as for example the slots 55, and the screws 20 56, adapted to clamp the cards in the slots. A skirt 57, may be provided for hiding the operative parts beneath the head piece.

Operations.—As the frame 1 is vibrated, or moved up and down, in any suitable manner, the figures 23 to 28 inclusive, on stems 30, setting in the socket pieces 19, are moved up and down. The stems slide in the socket pieces 19, and act as guides. Contact between the socket pieces 19, and the movable 25 figures, is through resilient stops 32. As the socket pieces strike against the stops the blow is cushioned, and the noise diminished and made practically imperceptible.

As the figures are moved up and down, 30 the springs 40 are moved into and out of contact with the surface of the platform. As the springs 40 make contact with the platform they will be compressed and there will be a resultant reactive force, which in 40 most cases will be diagonal to the direction of movement of the vibratory frame 1, hence it will produce a turning or rotary movement of the figures. The rotary or turning movement will not be uniform and will hence produce a movement creating 45 greater interest and expectation in the mind of the passerby or spectator. By hinging the parts such as legs and arms, the figures shown in Figs. 5 and 6, will give 50 added interest in the device. The stiffened thigh joint of the dependent part to which the spring is attached, Figs. 5 and 6, insures that there will be a substantial reaction between the spring and the figures.

55 The inventive idea herein set forth may receive other embodiments than those herein specifically illustrated and described.

What is claimed is:—

1. An advertising or amusement device 60 comprising a vibratory frame, a platform, an article to be actuated by said frame, and a connection between said frame and article, said connection comprising a socket piece and a rod, and a resilient stop through 65 which said rod bears upon the socket piece,

one part of said connection being carried by said vibratory frame.

2. An advertising or amusement device comprising a vibratory frame, a platform, an article to be actuated by said frame, and a connection between said frame and article, said connection comprising a socket piece and a rod, and a resilient stop through which said rod bears upon the socket piece, one part of said connection being carried by said vibratory frame, the said parts of said connection being relatively rotatable. 75

3. An advertising or amusement device comprising a vibratory frame, a platform, an article to be actuated by said frame, and a connection between said frame and article, said connection comprising a socket piece and a rod, and a resilient stop through which said rod bears upon the socket piece, and means for rotating said article. 85

4. An advertising or amusement device comprising a vibratory frame, a platform, an article to be actuated by said frame, and a connection between said frame and article, said connection comprising a socket piece and a rod, and a resilient stop through which said rod bears upon the socket piece, and means for rotating said article, said means comprising a spring adapted to contact with said platform as said frame is 90 vibrated.

5. An advertising or amusement device comprising a vibratory frame, a platform, an article to be actuated by said frame, and a connection between said frame and article, 100 said connection comprising a socket piece and a rod, and a resilient stop through which said rod bears upon the socket pieces, and means for rotating said article, said means comprising a coiled spring adapted 105 to contact with said platform as said frame is vibrated.

6. An advertising or amusement device comprising a vibratory frame, a platform, an article to be actuated by said frame, and a connection between said frame and article, said connection comprising a socket piece and a rod, and a resilient stop through which said rod bears upon the socket pieces, and means for rotating said article, said 115 means comprising a looped coiled spring adapted to contact with said platform as said frame is vibrated.

7. An advertising or amusement device comprising a vibratory frame, a platform, an article to be actuated by said frame, and a connection between said frame and article, said connection comprising a socket piece and a rod, and a resilient stop through which said rod bears upon the socket pieces, 125 and means for rotating said article, said means comprising a spring adapted to contact with said platform as said frame is vibrated, said platform being roughened to coact with said spring. 130

8. An advertising or amusement device comprising a vibratory frame, a platform, an article to be actuated by said frame, and a connection between said frame and article, 5 said connection comprising a socket piece and a rod, and a resilient stop through which said rod bears upon the socket piece, said figure having a pivoted depending part, said spring being attached to said pivoted 10 part.

9. An advertising or amusement device comprising a vibratory frame, a platform, an article to be actuated by said frame, and a connection between said frame and article, 15 said connection comprising a socket piece and a rod, and a resilient stop through which said rod bears upon the socket piece, said figure having a leg pivoted at the knee joint and stiff at the thigh joint, said spring 20 being attached to said leg.

10. An advertising or amusement device comprising a vibratory frame, a platform, an article to be actuated by said frame, and a connection between said frame and article, 25 said connection comprising a socket piece and a rod, and a resilient stop through which said rod bears upon the socket piece, said figure having a leg pivoted at the knee joint and stiff at the thigh joint, said spring

being attached to said leg, said figure having another pivoted leg pivoted at the knee and thigh joints and short enough not to come into contact with the platform during the working of the device. 30

11. An advertising or amusement device 35 comprising a vibratory frame, a platform, an article to be actuated by said frame, and a connection between said frame and article, said connection comprising a socket piece and a rod, and a resilient stop through 40 which said rod bears upon the socket piece, said figure being attached to said rod and said resilient stop being mounted upon said rod.

12. An advertising or amusement device 45 comprising a vibratory frame, a platform, an article to be actuated by said frame, and a connection between said frame and article, said connection comprising a socket piece and a rod, and a resilient stop through 50 which said rod bears upon the socket piece, said figure being attached to said rod and said resilient stop being mounted upon said rod, said rod constituting a guide for said stop. 55

In witness whereof I have hereunto signed my name.

CLINTON H. LEGGETT.
